AUTOMATIC CHAIN AND ANCHOR WASHER

John R. Heleba, Center Rutland, Vt.

Application January 30, 1953, Serial No. 334,180

4 Claims. (Cl. 114—179)

1

This invention relates to apparatus for cleaning the cables or anchor chains and anchors of vessels, and more particularly to an improved device for washing mud, clay and similar debris from the anchor chain and anchor of a vessel when the anchor is pulled up.

A main object of the invention is to provide a novel and improved anchor chain and anchor washing device which is simple in construction, which involves a minimum number of parts, and which provides a thorough washing action on the anchor chain and anchor of a vessel when the anchor is pulled up.

A further object of the invention is to provide an improved washing device for cleaning the anchor chain and anchor of a vessel, said device involving inexpensive parts, being durable in construction, and providing a means of washing debris such as mud or the like from all parts of an anchor chain and anchor of a vessel.

Further objects and advantages of the invention will become apparent from the following description and claims, and from the accompanying drawings, wherein:

Figure 1 is a side elevational view of the forward portion of the hull of a vessel equipped with an improved anchor chain and anchor washing device constructed in accordance with the present invention.

Figure 2 is an enlarged cross sectional view taken on the line 2—2 of Figure 1.

Figure 3 is an enlarged vertical longitudinal cross sectional view taken through the hawse pipe of the vessel illustrated in Figure 1.

Figure 4 is a fragmentary cross sectional view taken on the line 4—4 of Figure 3.

Referring to the drawings, 11 designates the hull of a vessel, said hull being provided with a hawse pipe 12 which slopes downwardly and outwardly from the deck 13 of the vessel and which is connected to the intermediate portion of an enlarged, anchor-receiving recess 14 formed in the side of the hull 11. Designated at 15 is the anchor chain which is wound on the drum of a conventional windlass 16, and designated at 17 is the anchor, said anchor being connected in the conventional manner to the end of the chain 15. The chain 15 passes through the hawse pipe, as illustrated in Figure 1.

As shown in dotted view in Figure 1, the windlass 16 may be operated to pull the chain so that the anchor may be substantially fully housed in the hawse pipe and recess 14, the anchor stock 18 being substantially fully receivable inside the recess 14.

2

Designated at 19 is a helically coiled main conduit which extends around the hawse pipe 12, the helically coiled conduit 19 being substantially coextensive in length with the hawse pipe and being connected at its upper end through a valve 20 to a pipe 21 which is in turn connected to a source of water under pressure. The convolutions of the conduit 19 each have a plurality of spaced conduits 22 projecting therefrom with the free ends thereof connected in communication with the inturn of the hawse pipe 12 so that they are directed toward the axis of the hawse pipe, as shown in Figure 2. The lower end of the helically coiled conduit 19 is provided with the closure plug 23, shown in Figure 3.

Designated at 24 is an additional conduit which is disposed around the margin of the enlarged anchor-receiving recess 14, as shown in Figures 1, 3 and 4, said conduit 24 being connected to the recess 14 by a plurality of uniformly spaced, inwardly directed, substantially radial conduit elements 25 extending from the conduit 24 to the wall of the recess 14. As will be clearly apparent from Figure 3, the inwardly directed radial conduit elements 25 are arranged substantially around the entire circumference of the recess 14 and are directed inwardly towards its axis. As shown in Figure 3, the conduit elements 25 may be inclined slightly outwardly. One end of the conduit 24 is provided with the closure plug 26, and the other end of the conduit 24 is connected through a valve 27 to the water supply pipe 21.

In operation, the chain 15 may be washed as it is pulled upwardly by the windlass 16 by opening the valve 20, whereby the chain is washed by the inwardly directed water jets emerging from the conduit elements 22. As the anchor 17 is drawn upwardly into the hawse pipe, the stem thereof is washed by the water jets from the conduit elements 22, and the remainder of the anchor may be washed by opening the valve 27. The valve 27 is opened when the anchor has been drawn upwardly to the dotted view position thereof shown in Figure 1, wherein the stock 18 of the anchor is substantially completely housed inside the recess 14. The opening of valve 27 allows the water under pressure to enter the conduit 24, and provides inwardly directed, substantially radial jets of water around the margin of the recess 14, said jets acting upon substantially the entire surface of the anchor stock 18, as well as on the stem of the anchor to clean the anchor completely and to remove all mud, clay, and similar debris therefrom. After the cleaning

operation, the valves 27 and 28 may be closed, and the anchor may be retained in its elevated position as long as necessary.

As shown in Figure 3, the inwardly directed conduit elements 22 are preferably inclined at an angle of approximately 45° with respect to the axis of the hawse pipe 19, the inclination of the conduit elements 22 being such that the debris washed from the anchor chain and anchor will be carried downwardly through the hawse pipe and out of the recess 14.

While a specific embodiment of an improved anchor chain and anchor cleaning device for a vessel has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. In a vessel having an anchor chain and an anchor attached thereto, means for cleaning the chain and anchor comprising a hawse pipe sloping downwardly and outwardly from the deck of the vessel to a side of the vessel's hull, a main conduit coiled helically around said hawse pipe and being adapted to be connected to a source of water under pressure, and a plurality of spaced conduits projecting from each of the convolutions of said main conduit and having the free end thereof connected in communication with the interior of said hawse pipe so that they are directed toward the axis of said hawse pipe, whereby water under pressure may be directed into said hawse pipe to clean the chain and anchor.

2. In a vessel having an anchor chain and an anchor attached thereto, means for cleaning the chain and anchor comprising a hawse pipe sloping downwardly and outwardly from the deck of the vessel, the side of the hull of the vessel being formed with an enlarged anchor-receiving recess and the hawse pipe being connected to and terminating at the intermediate portion of said recess, a main conduit coiled helically around said hawse pipe and being adapted to be connected to a source of water under pressure, a plurality of spaced conduits projecting from each of the convolutions of said main conduit and having the free end thereof connected in communication with the interior of said hawse pipe so that they are directed toward the axis of said hawse pipe, whereby water under pressure may be directed into said hawse pipe to clean the chain and anchor, and means for directing additional water under pressure into said recess.

3. In a vessel having an anchor chain and an anchor attached thereto, means for cleaning the

chain and anchor comprising a hawse pipe sloping downwardly and outwardly from the deck of the vessel, the side of the hull of the vessel being formed with an enlarged anchor-receiving recess and the hawse pipe being connected to and terminating at the intermediate portion of said recess, a main conduit coiled helically around said hawse pipe and being adapted to be connected to a source of water under pressure, a plurality of spaced conduits projecting from each of the convolutions of said main conduit and having the free end thereof connected in communication with the interior of said hawse pipe so that they are directed toward the axis of said hawse pipe, whereby water under pressure may be directed into said hawse pipe to clean the chain and anchor, and means for directing additional water under pressure into said recess, said last-named means comprising a conduit disposed around the margin of said recess, means connecting said last-named conduit to the source of water under pressure, and a plurality of spaced inwardly directed substantially radial conduit elements connecting said last-named conduit to the wall of said recess.

4. In a vessel having an anchor chain and an anchor attached thereto, means for cleaning the chain and anchor comprising a hawse pipe sloping downwardly and outwardly from the deck of the vessel, the side of the hull of the vessel being formed with an enlarged anchor-receiving recess and the hawse pipe being connected to and terminating at the intermediate portion of said recess, a helically coiled first conduit surrounding said hawse pipe, means connecting said first conduit to a source of water under pressure, a plurality of spaced conduits projecting from each of the convolutions of said main conduit and having the free end thereof connected in communication with the interior of said hawse pipe so that they are directed toward the axis of said hawse pipe, whereby water under pressure may be directed into said hawse pipe to clean the chain and anchor, a second conduit disposed around the margin of said recess, means connecting said second conduit to the source of water under pressure, and a plurality of spaced inwardly directed conduit elements connecting said second conduit to the wall of said recess.
